Application SN 29/047,797—Now Abandoned.

Primary Examiner—Brian N. Vinson[57] CLAIM

The ornamental design for improved combined toilet tissue holder and grab bar, as shown and described.

DESCRIPTION

FIG. 1 is a perspective view of the combined toilet tissue holder and grab bar;

FIG. 2 is an elevational view from one side of the bar shown in FIG. 1, and,

FIG. 3 is a rear elevational view of the bar shown in FIGS. 1 and 2.

The view opposite FIG. 2 is an exact mirror image of that figure.
